UNITED STATES PATENT OFFICE.

HARRY W. HARDINGE, OF NEW YORK, N. Y., ASSIGNOR TO HARDINGE COMPANY, OF NEW YORK, N. Y., A CORPORATION OF DELAWARE.

GRINDING-MILL AND GRINDING MEDIUM THEREFOR.

1,388,463.

Specification of Letters Patent. Patented Aug. 23, 1921.

Application filed July 8, 1920. Serial No. 394,636.

To all whom it may concern:

Be it known that I, HARRY W. HARDINGE, a citizen of the United States of America, residing at New York, in the county and 5 State of New York, have invented certain new and useful Improvements in Grinding-Mills and Grinding Media Therefor, of which the following is a full, clear, and exact description.

10 This invention relates to the art of grinding mills and has for one of its principal objects to provide grinding media particularly adapted to disintegrate the material acted upon by an abrasive or tearing apart 15 action.

Grinding mills embodying a rotatable barrel or drum containing a multiplicity of loose grinding members or media are now well known in the art. The barrel or drum 20 assumes various forms such as a cylinder, cone or other suitable shape. The loose grinding media assume the form of balls, pebbles, rods, etc. The grinding media roll and tumble about freely in the rotation of 25 the drum and disintegrate the material fed to the mill primarily by an impact action.

I have found that disintegration by impact action or pounding is often injurious and ruinous to certain material, particularly fibrous material such as jute, wood pulp, etc. Moreover, the time and power required to reduce such material as well as copper, brass, aluminum, etc. (which resist the hammer action of pounding and rolling 35 bodies) to a given degree of fineness are comparatively high in magnitude. The above mentioned materials are more effectively and efficiently reduced to fines or powder by an abrasive tearing rather than by the crushing impact which is most effective in 40 breaking up quartz and similar materials.

In order to secure the desired abrasive action I have devised comparatively flat grinding members which possess little or 45 no tendency to roll when rotated in the mill of which they form a part, but rather slide and abrade or tear the material lying between each grinding member and its neighbors. Other objects and advantages will 50 appear in view of the following disclosure of some of the various specific forms which the invention may assume.

Referring to the drawings which illustrate what I now consider preferred forms 55 of my invention.

Figure 1 is an elevation of one of the numerous forms of mills in which my grinding media may be employed.

Figs. 2 and 3 are respectively a plan view and a side elevation of one form of grinding member.

Fig. 4 is a view similar to Fig. 2 but illustrating a modified form of grinding member.

Fig. 5 is a section on the line 5—5 of Fig. 4.

Figs. 6 and 7 are elevations of two further modifications which may have the appearance, in plan, illustrated in Figs. 2 and 4 respectively.

Fig. 8 is a diagrammatic view employed 70 in explaining the operation of the invention.

It will be understood that the grinding media forming a part of the present invention may be employed in various types of mills such as cylindrical, conical, etc., and the invention includes such use. In order to avoid surplusage in illustration and description and because the conical mill is at present preferred by me I have illustrated only a form of the last mentioned type of mill. Calling attention to Fig. 1 it will be seen that the mill there illustrated comprises a hollow drum 1 having a conical outlet portion 2 and mounted for rotation in bearings 3, 3 by means of a gear wheel 4 and suitable impelling means (not shown). Material to be ground or disintegrated may be introduced through the inlet trunnion 5, and after having been reduced to the desired fineness in the drum, the resulting fines are discharged through the outlet trunnion 6. The drum 1 has loosely mounted therein a multiplicity of flat (as compared to balls) grinding members 7 which may assume various forms as will hereinafter appear.

One form of grinding member is illustrated in Figs. 2 and 3 and is in the form of a flat discus-shaped element of metal or other suitable material. It will be apparent that when a multiplicity of such members are contained or placed in a conical or other drum 1 they tend to assume the relative position illustrated in full lines in Figs. 1 and 8. The reason for this is that this is the position of stable equilibrium of the members.

7. As the drum 1 rotates the upper members 7 slide or slip down over the adjacent members, instead of rolling down, and thereby tear or separate by abrasion the material in the interstices between the said members.

The action is therefore one of separation or distintegration by abrasion or tearing in contradistinction to disintegration by impact or crushing as in the case of rolling 5 grinding media. I wish to emphasize that the tendency of the members 7 to roll during the operation of the mill is minimized as will be clearly apparent on inspection of Fig. 8. In order for any member 7 to roll 10 it must assume the position shown in dotted lines in the last mentioned figure. Due to the fact that this is an exceedingly unstable position the chance that any member 7 will assume this dotted line position or that it 15 will maintain such position for an appreciable length of time is so remote as to be practicably negligible.

In order to enhance the abrading or tearing action the surfaces of the members 7 20 may be roughened or rendered grid-like as indicated in Fig. 2 (the surfaces being shown smooth in Fig. 3 for the sake of clearness in illustration). Instead of, or in addition to roughening the surfaces of the members 25 7, each of said members may be provided with openings 8 extending into or through the members. These openings, when provided, accomplish a very important result especially when grinding wet pulp or 30 similar material. The material flows into and fills the said openings and joins the material lying on each side of the members 7 by what may be termed a plurality of keys similar to the keys which hold plaster or cement 35 to lathing. During the operation of the mill and the consequent sliding of each member 7 across its neighboring members the fibrous pulp or other material is effectively torn apart.

40 While the form of grinding member specifically described above is at present preferred by me it will be obvious that it may be modified without departing from the scope of the broadest claims hereinafter 45 stated. For example instead of employing circular discus-like members, flat discus-like members having polygonal edges may be employed, as indicated in Figs. 4 and 5. Or flat cylinders or flat prisms or ovals may be 50 employed as indicated in Figs. 6 and 7 respectively.

If a conical mill, and such a mill is illustrated in Fig. 1, is employed it will be borne in mind that there is an inherent classification by size on the interior of the drum 1 55 when the latter is rotated. In other words the coarsest particles of material lie adjacent the base of the cone-frustum 2 and the particles diminish in size as the outlet 6 is approached.

60 While the members 7 employed in any particular will be all of the same size, an important effect may be achieved by providing

members of varying sizes. It will be apparent that the abrasive action between a member 7 and its lower neighbors is to a large extent dependent on the weight and therefore size of the member. When the material is coarsest, *i. e.*, at or adjacent the base of the cone 2, it is desirable to exert the maximum abrasive action and it is desirable progressively to diminish this abrasive action as the material decreases in size, in other words in the direction of approach to the outlet 6. If, as above stated, the members 7 employed 70 in a mill such as the one illustrated are of varying sizes they will be automatically classified according to size in the same manner that the material is. The result is that the abrasive action will be a maximum at or 75 adjacent the base of the cone 2 and will gradually diminish in the direction of the outlet opening.

In accordance with the provisions of the patent statutes, I have herein described the 80 principle of operation of my invention, together with the apparatus which I now consider to represent the best embodiments thereof, but I desire to have it understood that the apparatus disclosed is only illustrative and that the invention can be carried out by other means. Also, while it is designed 85 to use the various features and elements in the combination and relation described, some of these may be altered and others omitted 90 without interfering with the more general results outlined, and the invention extends 95 to such use.

What I claim is:

1. A grinding mill comprising in combination, a rotatable drum containing a multiplicity of discus-shaped elements relatively 100 slidable with respect to each other and free to assume a position in which their geometrical axes are at a substantial angle to the axis 105 of rotation of said drum, each of said elements comprising two cone portions secured base to base, the altitude of each cone portion being small as compared to the diameter of its base.

110 2. A grinding mill comprising in combination, a rotatable drum containing a multiplicity of discus-shaped elements relatively 115 slidable with respect to each other and free to assume a position in which their geometrical axes are at a substantial angle to the axis of rotation of said drum, each of said elements comprising two cone portions secured base to base, the altitude of each cone portion being small as compared to the diameter 120 of its base, and each of said elements having a plurality of openings extending therethrough from one face to the other.

In testimony whereof I hereto affix my signature.

HARRY W. HARDINGE.
